UNITED STATES PATENT OFFICE.

JOHN R. HAWKEY, OF PARK HILL, ONTARIO, CANADA.

SPRING-GEAR FOR BUGGIES.

SPECIFICATION forming part of Letters Patent No. 292,811, dated February 5, 1884.

Application filed August 22, 1883. (No model.)

To all whom it may concern:

Be it known that I, JOHN RUNDLE HAWKEY, of the village of Park Hill, in the county of Middlesex, in the province of Ontario, Canada, carriage-builder, have invented certain new and useful Improvements on Spring-Gear for Buggies; and I do hereby declare that the following is a full, clear, and exact description of the same.

10 The invention relates to certain new and useful improvements in spring-gear of that class in which the body of the vehicle is carried as low as a side-bar buggy or carriage, while retaining at the same time the full benefit of the elastic action and durable qualities of a full elliptic-spring gear; and it consists in the peculiar combinations, construction, and arrangement of parts, as hereinafter more fully described and claimed.

20 The drawing represents a perspective view, showing my improved spring-gear.

The lower the body of a buggy can be carried the more popular it is with the public, and therefore manufacturers of buggies have 25 devised many arrangements of spring-gear for accomplishing the desired end; and I am aware that it is not new to attach a vehicle-body to braces secured to the side bars, instead of directly to the side bars, and do not 30 claim, broadly, such constructions.

In my invention I employ the side bars, A, as usual, and clip onto the side bars the iron hanger B. This hanger, it will be noticed, has a center plate, a, upon which the elliptic spring 35 C is clipped. It will also be noticed that the

hanger B has parallel bifurcated arms b extending from the plate a to the side bars, A. By thus dividing the hanger B the ends of the elliptic spring C are permitted to fit between the arms b of the hangers, and in this manner 40 the springs C will work freely below the side bars, A. The arms b, being on each side of the spring C and parallel therewith, form guards to prevent the spring being twisted or thrown out of this square, and thus obviate 45 the necessity for the braces generally employed for bracing an elliptic spring.

d are braces or stays joining together the arms b on opposite sides of the plate a. The hanger B is in this manner strengthened, and 50 by the employment of the braces d, I am able to make hangers of much lighter material than if the braces were dispensed with.

Although my invention is specially designed for buggies, it is of course applicable to vehicles of other description, and although I illustrate the employment of the ordinary side bars, it will of course be understood that an equivalent for the side bars might easily be designed.

60 What I claim as my invention is—

The plate a, having bifurcated arms b extending obliquely from either side of it, in combination with the braces d, substantially as and for the purpose specified.

Toronto, August 16, 1883.

JOHN R. HAWKEY.

In presence of—

CHAS. C. BALDWIN,
LEWIS TOMLINSON.
